PNEUMATIC TIRE

Donald L. Munoz, Sterling Heights, Mich., assignor to
Uniroyal, Inc., New York, N.Y.

Filed Aug. 15, 1969, Ser. No. 18,705

Term of patent 14 years

Int. Cl. D12—14

U.S. Cl. D90—20

FIG. 1 is a perspective view of a pneumatic tire embodying my new design, it being understood that the borders of the segments of the sidewall are of a color contrasting with the color of the background of the sidewall and contrasting with the color of the areas enclosed by the borders of the segments.

FIG. 2 is an elevational view of the tire of FIG. 1 to a reduced scale, the opposite sidewall being the same except for the omission of the segments; and

FIG. 3 is a fragmentary sectional view, to an enlarged scale, of a tire cross section taken substantially on the plane indicated by line 3-3 of FIG. 1.

The characteristic feature of my design resides in the above-mentioned segments of the sidewall.

I claim:

The ornamental design for a pneumatic tire, substantially as shown and described.
